SYSTEM OF ILLUMINATION

Norman I. Prosser, Long Beach, Calif.

Application August 7, 1931, Serial No. 555,850

9 Claims. (Cl. 200—118)

This invention relates to a system for illuminating gas discharge tubes.

Such tubes are now well-known and are extensively used for advertising and display purposes. They usually include a filling of an inactive gas that can be ionized by impressing a sufficiently high potential difference across the tube, as by the aid of appropriate electrodes. A common form of such tubes is that utilizing a noble monatomic gas, such as neon, argon or helium, or a mixture thereof, at a pressure of the order of from four to twenty millimeters of mercury.

Such tubes can be operated to be brilliantly luminescent at a current consumption of about 20 to 30 milliamperes. Constant current transformers are usually utilized to provide a uniform current to any length of tubing within the limits of the transformer capacity, and up to about 15,000 volts.

Such tubes, to attract more attention, have been flashed, that is, instantaneously and intermittently energized. The attractiveness can be still further enhanced by moving the tube during such intermittent energization, as by mounting it on a disc that can be rotated. When the speed of rotation is sufficient and the periods of energization are short enough, the persistence of vision produces the effect of a large number of tubes simultaneously energized. If a plurality of tubes of different colors are mounted on a common disc, and each flashed so that at times their periods of illumination overlap, and at other times do not, a changeable effect of great attractiveness is obtained.

It is one of the objects of my invention to provide a simple and effective system for flashing one or more such tubes, either stationary or rotating.

It is another object of my invention to provide a simple and convenient flasher mechanism for this purpose.

More particularly, the flasher utilized with the tubes is of the thermal type, where alternate heating and cooling of a metal member serves to open and close the energizing circuit. Although such thermostatic control devices are in general well-known, I utilize a novel heating principle that has the advantage of simplicity and inexpensiveness.

Thus I utilize the heat generated adjacent the contacts for operating the metal parts. This can be accomplished by appropriate choice of materials for the contacts, which offer such a resistance to the passage of current as to pro-

duce the required heat; or else by arcing the current between contacts and utilizing the heat of the arc for this purpose.

My invention possesses many other advantages, and has other objects which may be made more easily apparent from a consideration of several embodiments of my invention. For this purpose I have shown a few forms in the drawings accompanying and forming part of the present specification. I shall now proceed to describe these forms in detail, which illustrate the general principles of my invention; but it is to be understood that this detailed description is not to be taken in a limiting sense, since the scope of my invention is best defined by the appended claims.

Referring to the drawings:

Figure 1 is a diagram illustrating the mode of operation of my invention;

Figs. 2 and 3 are diagrams showing various applications of my invention to luminous tube systems;

Fig. 4 is a diagram of another form of my invention;

Fig. 5 is an enlarged fragmentary view of a modified form of contacts used with my invention; and

Fig. 6 is a diagram of still another form of the invention.

In Fig. 1 there is disclosed a luminous tube 11 of indefinite length, having conductors 12 and 13 for impressing an energizing potential across the column of gas in the tube. Internal electrodes 14, 15, are indicated. The energizing potential is shown as supplied by the secondary or high potential coil 16 of a constant current transformer 17. The primary coil 18 is shown as connected to commercial mains 19 of low potential.

I provide a flasher mechanism which periodically serves to deenergize the tube 11, as by short circuiting it. Since transformer 17 is of the constant current type, such short circuiting does not harmfully raise the current flow through the transformer coils. This short circuiting is accomplished by the aid of a pair of contact points 20, 21.

Contact point 20 is stationary and is connected to one side of the coil 16. The other contact point 21 is movably mounted on a bi-metallic strip 22, which is so arranged as to flex downwardly when its temperature increases materially above room temperature. This strip is fastened at that end remote from the contact 21, on a block 23, and a post 24 connects 55

this end of the strip to the other side of coil 16.

It is apparent that when current flows between contacts 20, 21, the resistance of the path including strip 22, and these contacts, is so much less than the resistance of tube 11 that the potential drop across this shunt circuit is insufficient to light tube 11. Therefore all of the current flows through this shunt circuit and the tube stays dark. As soon as the contacts separate to an extent such that the potential difference across this shunt circuit is greater than that required to energize the tube 11, current will flow through the tube and it will be energized.

The relative movement of the contacts 20 and 21 is obtained by transferring heat to the bimetallic strip 22. This can be accomplished by providing contacts 20, 21 of such material such as carbon, which would heat up due to their resistance. The lower contact 21 being in good thermal exchange relationship to the strip 22, causes this strip to be heated and therefore flex downwardly, breaking the shunt circuit and causing tube 11 to luminesce. Since current then no longer flows through the contacts, there is no creation of heat, and the bimetallic strip after a short interval, assumes its normal cold position. The shunt circuit is then again energized, and the cycle is repeated.

I find it advantageous, however, to utilize the heat of an arc across the contacts 20, 21 for heating the bimetallic element 22. For this purpose, the normal unflexed position of the strip 22 positions the contact 21 merely within arcing distance, and not in actual contact with contact 20. Contact 21 is, of course, made of material that can withstand arcing. The spacing of the contacts 20, 21 is such that the arcing resistance is much less than the tube resistance while the tube is deenergized and accordingly an arc forms between the contacts and no current flows through the tube 11.

As soon as sufficient heat is transferred to member 22, it flexes downwardly and draws out the arc. The arc resistance then increases. When it reaches the position 26 the arc resistance may be as great as the normal resistance of tube 11, but the voltage developed thereby is insufficient to strike the tube. When it is sufficient to produce a potential difference to "strike" the tube 11, this tube is energized and robs the arc of current. This condition is represented by the dotted position 25 of the member 22. The tube voltage then decreases and current passes through it to the exclusion of the arc.

Now the member 22 begins to lose heat by radiation, because the arc is extinguished. In losing heat, it starts to return to the former position. Since it is necessary for the contacts 20, 21 to approach closer to strike the arc after it is once extinguished, there being no ionized air to support the arc, the arc does not again become active until the member 22 returns to the full line position, when the cycle is repeated.

This mode of intermittent operation can be applied to a plurality of tubes in series, each tube being shunted by its own flasher mechanism. Such a system is illustrated in Fig. 2. Here the transformer 27 of the constant current type supplies all of the tubes 28 to 32 inclusive. Each tube is independently controlled by its flasher, such as 33, which shunts the tube.

For successful operation, the tubes should be long enough so that the striking voltage will correspond to an appreciable separation of the flasher contacts, say at least one-thirty-second of an inch.

A plurality of tubes could also be arranged in parallel, and still utilize the principle of the invention. This is illustrated in Fig. 3. In this case, the constant current transformer 34 can supply a plurality of circuits in parallel. Since the tube circuits are similar, but one will be specifically detailed. Each tube circuit includes a tube 35 and a flasher device 36 in series with it. In this case, since the tube resistances depend upon a number of factors such as the composition and pressure of the gas, the length of the tube, the construction of the electrodes, and the amount of current passing through the tube, these resistances are not the same for any of the tubes. Consequently, an arc will form at 20 that flasher mechanism which is in the circuit of least resistance, and all of the current will flow through the arc between the contacts and the associated tube in series. As the arc heats the bimetallic strip, the strip flexes and the air gap lengthens. The arc continues to act until the combined series resistance of the arc and tube exceeds the combined air gap and tube resistance of another circuit. By arranging the switches to cool slowly, as by providing appropriate heat insulation, the tubes can be illuminated one after another in the group. If the cooling is so slow that none of the switches have returned to normal position by the time each tube has been illuminated, an auxiliary tube 37 can be connected directly across the transformer 34, said tube having a higher resistance than any of the parallel circuits, but within the scope of operation of the transformer 34. This tube will light during the interval until at least one of the switches returns to normal. This tube is thus a safety device to prevent any unusual high voltages, and can also be used as an additional flashing device.

The bimetallic bar 22 is preferably made by attaching a brass strip to a relatively in-expansible strip, so that when heated, the brass strip only elongates and produces the flexure. This bimetallic element can be controlled in a practicable manner as disclosed in Fig. 4. In this case the bimetallic element 38 has an inverse bend something like an S. One end is rigidly fastened to a block 39. This block carries the post 40 for connecting it to one terminal of the secondary coil 41 of the transformer 42. The other end of the strip 38 engages a notch 43 in an adjustable spring socket 44. This socket is formed of a U spring, one leg being rigidly fastened to a block 45, and the other leg carrying the notch 43. A screw 46 can be used to urge this leg outwardly and thereby to adjust the free position of the strip 38.

The non-expansible side of this strip is at the top in this form. It carries a contact 47 which cooperates with a stationary contact post 48. The normal spacing of these contacts can be adjusted by providing a block 49 in which post 48 is threaded. Further adjustment of the position of strip 38 is provided by the aid of a finger or stop 50 supported on block 39 and urged downwardly to engage the strip 38 beyond the convex left hand portion thereof. Adjustment of finger or stop 50 is provided by a screw 51 engaging the finger.

The arrangement is such that under normal

temperature conditions, the strip 38 is in the full line position; the contact 47 placed on the concave portion of the strip and closer to notch 43; and it is slightly above a line drawn from the one end of the strip to the other. The members 50 and 44 are so adjusted that this position is attained, and post 48 is adjusted for providing the desired air gap between it and contact 47. The air gap between members 47 and 48 is included in a series circuit with a discharge tube 52. The entire tube circuit can thus be traced as follows: coil 41, post 40, strip 38, contact 47, post 48, tube 52, back to coil 41.

With an arc formed between these contacts, the tube 52 is illuminated. As heat accumulates due to the arc, the lower brass portion of strip 38 expands and the concave part upon which contact 47 is supported, lowers toward a position shown by the dotted lines 53. When the contact 47 moves far enough to carry it to or just below the line joining the ends of the strip 38, it snaps through the center. Appropriate stopping means can be provided for the strip. For example, an adjustable post 55 can cooperate with a lower contact 54, and can also serve to control another circuit, in a manner to be hereinafter explained.

The resilient anchor 44 permits the member 38 to snap over center. It is apparent that the stop 50 and this anchor 44 cooperate to define the normal configuration of the strip; and this configuration can be varied by appropriate adjustment of these two elements. The post 48 can then be adjusted to provide the proper arcing distance. The snap over action when sufficient heat accumulates is pronounced and rapid, and causes the air gap between contacts 47, 48 to be so great that current flows by preference through a path alternative to the tube 52, as will be now described. The back contact 54 as before stated, cooperates with the post 55 to limit the backward movement. This back contact rests firmly against the post 55 and can be made from good contact metal such as tungsten.

These back contacts can control an alternative circuit from transformer coil 41, to strip 38, contacts 54, 55, a tube 56, back to the other side of coil 41. Since the contact 54 rests securely against post 55, there is no material evolution of heat, and the strip 38 loses heat by radiation when these contacts are in engagement. As the strip tends to move away from post 55, it is opposed by a force due to the resilience of member 44. This member acts to keep the right hand portion of strip 38 bent downward, toward post 55. However, upon sufficient contraction of the brass part of strip 38, the resilient force of member 44 is overcome and there is a rapid snap over action to the full line position of Fig. 4. The cycle is then repeated. By proper adjustment of the parts, very little movement is required of contact 47 before it snaps over; and correspondingly, there is no perceptible movement of contact 54 from post 55 until the snap over action takes place to the full line position. Accordingly, there is no danger of producing any material heat when the back contacts are active, since no arc forms at these contacts.

It is apparent that the potential difference delivered by coil 41 must be sufficient to provide the arcing voltage between contacts 47, 48, as well as the striking voltage of tube 52. The system of Fig. 4 can be used to energize the two tubes 52 and 56 alternately; although either may

be removed from the circuit if desired. The time interval of flashing is controlled by the compression at notch 43, the shape of strip 38, and the distance of travel between the contact 54 and post 55.

The adjustable stop 50, which helps to define the shape of strip 38, is an important element. In lieu of this form of stop, the form shown in Fig. 5 can be used. In this case, an insulation point 57 is inserted into the post 48 and acts to space the end of the post from the cooperating arcing contact 47. In order to withstand the heat generated by the arc as well as the pounding of the contact 47, proper insulation material should be chosen for this point 57. A quartz tip has been found practical, which can be soldered in place and can project about one-sixty-fourth of an inch beyond the end of post 48.

A definite stop limiting the spacing of contacts 47, 48 is important, for it ensures that the strip 38 will always return, when cool, to the same configuration and with precisely the same air gap separation of contacts 47, 48. Thus any objectionable flicker due to lengthening of the gap is prevented.

The tubes shown in Fig. 4 can be either stationary or rotating and of different colors. A more complex system, involving three tubes, is illustrated in Fig. 6. In this case, the secondary coil 58 of a high voltage constant current transformer 59 is shown as being divided into two sections, as by a ground connection 60. In a well designed transformer, either of these sections could be short circuited without interfering with the operation of the other section.

The right hand section of coil 58 is arranged to flash a stationary tube 61 that may be used to form stationary letters or characters, alternately with a revolving tube 62. This flashing function is accomplished by a mechanism such as described in Fig. 4, having the bimetallic strip 64, arcing contacts 65, and back contacts 66. The circuits for this part of the system can be traced as follows: from the right hand end of the right hand half of coil 58, to strip 64, where the current finds alternative paths; either through front contacts 65, connection 67, tube 62, and collector ring 68, or if the strip 64 is heated to make back contacts active, then through back contacts 65, and tube 61. At ground 69 these alternative paths recombine, and continue through ground 60 to the other side of the coil section.

It is apparent that tubes 62 and 61 will be alternatively energized by the alternate operation of the front contacts 65 and the back contacts 66.

The third tube 70 is also shown as rotating, but is intended to be energized by the left hand portion of coil 58. The flashing of this tube is accomplished by a flasher mechanism 71 having front contacts 72 and rear contacts 73. When the front contacts 72 are active, the left hand section of coil 58 is short circuited. This short circuit can be traced as follows: from the left hand end of the left hand portion of coil 58, to device 71, front contacts 72, connection 74 to the center connection of coil 58. When the back contacts 73 are active, the revolving tube 70 is illuminated, through the following circuit: from the left hand end of the left hand portion of coil 58, to device 71, back contacts 73, tube 70, collector ring 68, and grounds 69, 60 to the center connection of coil 58.

The tubes 62, 70 may be of contrasting colors,

and each may have different colors along its length. They may be rotated on a common support. In such case, the periods of actuation of devices 63, 71 can be such as to be unequal, whereby overlapping of the tube energization can be secured with attendant brilliant displays.

I claim:

1. In a current controlling device, a bimetallic strip, a stationary support for one end of the strip, a resilient anchor for the other end of the strip and arranged to hold the strip resiliently in a reverse bend and to limit any displacement of said other end to a substantially endwise movement, and means whereby said strip can be heated.

2. In a current controlling device, a bimetallic strip, a stationary support for one end of the strip, a resilient anchor for the other end of the strip and arranged to hold the strip resiliently in a reverse bend and to limit any displacement of said other end to a substantially endwise movement, means whereby said strip can be heated, and means whereby the configuration of the strip can be adjusted so that it returns to that configuration substantially exactly when it returns to its cool condition.

3. In a current controlling device, a bimetallic strip, a stationary support for one end of the strip, a resilient anchor for the other end of the strip to hold it in a bent form and to limit any displacement of said other end to a substantially endwise movement, a current carrying part carried by the strip, and a stationary current carrying part cooperating therewith to produce heat by the passage of current between them, whereby the strip snaps over to interrupt the current.

4. In a flasher device, a stationary contact, a movable contact, a temperature responsive support for the movable contact and having one end rigidly anchored and the opposite end resiliently anchored to restrain any movement to an endwise direction, and means whereby current passing between the contacts generates heat to cause the support to separate the contacts for interrupting the current flow, said support upon such separation, cooling after a period to return the contacts to current flowing position.

5. In a flasher device, a thermostatic strip having a pair of positions corresponding to low and high temperatures of the strip and having one end rigidly anchored and the opposite end resiliently anchored to restrain any movement to an endwise direction, and a pair of contacts operated thereby, the current passing through said contacts during the low temperature position acting to generate heat to throw the strip to the high temperature position, said high temperature position being such that no current can then flow, permitting the strip to cool and

to return to its low temperature position for repeating the cycle.

6. In a flasher device, a thermostatic strip confined at one end to a stationary support and restrained at the other end to an endwise movement and capable of snapping from one stable position to another, corresponding respectively to a low and to a high temperature of the strip, and a pair of contacts operated by the strip, to be in current passing relationship during the position corresponding to low temperature, the current passing acting to generate heat to throw the strip to the high temperature open circulating position, where the strip can cool to return to the closed circuiting position for repeating the cycle.

7. In a flasher device, a stationary contact, a movable contact, a temperature responsive support for the movable contact and having one end rigidly anchored and the opposite end resiliently anchored to restrain any movement to an endwise direction, means for spacing the contacts within arcing distance for the passage of current between them and for heating the support, so as to cause it ultimately to separate the contacts beyond arcing distance to interrupt the current flow, said support upon such separation, cooling after a period to return the contacts to current flowing position.

8. In a flasher device, a thermostatic strip having a pair of positions corresponding to low and high temperatures of the strip and having one end rigidly anchored and the opposite end resiliently anchored to restrain any movement to an endwise direction, and a pair of contacts operated thereby, to cause them to approach to arcing position for the passage of current, and to separate them beyond arcing distance, said contacts during the low temperature position acting to generate heat by said arcing to throw the strip to the high temperature position, said high temperature position being such that no current can flow, thereby permitting the strip to cool and to return to its low temperature position for repeating the cycle.

9. In a flasher device, a thermostatic strip confined at one end to a stationary support and restrained at the other end to an endwise movement and capable of snapping from one stable position to another, corresponding respectively to a low and to a high temperature of the strip, and a pair of contacts operated by the strip, to be in arcing relationship during the position corresponding to low temperature, the current thus passing through the contacts acting to generate heat to throw the strip to the high temperature position beyond arcing distance where the strip can cool to return to arcing position for repeating the cycle.

NORMAN I. PROSSER. 60
